UNITED STATES PATENT OFFICE.

ALPINE B. ROSSON, OF VERNON, TEXAS, ASSIGNOR OF ONE-HALF TO JOHN CECIL CAMP, OF SAME PLACE.

HAME-HOOK.

SPECIFICATION forming part of Letters Patent No. 499,177, dated June 6, 1893.

Application filed February 9, 1893. Serial No. 461,675. (No model.)

To all whom it may concern:

Be it known that I, ALPINE B. ROSSON, a citizen of the United States, residing at Vernon, county of Wilbarger, and State of Texas, have 5 invented a new and useful Improvement in Hame and Trace Attachments, of which the following is a specification.

My invention relates to a hame and trace attachment, having for its object a simple, 10 strong and durable device which can be detached and replaced by the user without special skill or the use of tools when it becomes worn or broken. I attain this object by the mechanism illustrated in the accompanying drawings in which—

Figure 1, is a perspective view of the device as it is engaged by the staple of the hame and the trace chain. Fig. 2, is a detail front side view. Fig. 3, is a detail view of the double 20 hooked base. Fig. 4, is a detail view of the detachable fastening plate. Fig. 5, is the detail inside view of said detachable fastening plate.

Similar letters refer to similar parts throughout the several views.

25 A, designates the hame, B, the hame staple. C, designates the device composed of three parts: the detachable fastening plate C', the double hooked base C², and the key G. The detachable fastening plate C' has a longitudinal slot E to receive the ear D and the key G. The 30 slot E to receive the ear D and the key G engages the aperture g on the outside of said detachable fastening plate so that it holds the latter in place. Said detachable fastening plate C' has also a recess c² separating the 35 main plate from the tongue c, which unites with and closes the hook d forming with it a scarf at c' and d'. It also has a grooved or beveled shoulder c⁴, which fits into and closes hook F of the double hooked base C². The 40 inside of said detachable fastening plate may have depressions as designated by c³ and c³ or

have a plain surface. The double hooked base C² may be made either curved or straight. It has two open hooks F and d, both of which are closed and fastened as heretofore designated. 45 The beveled or grooved edge of said hook F is designated by f, and d² is the recess in hook d in which d' shows the notch made to form the scarf with the tongue c as heretofore designated. Said hook d can be made one-half 50 inch or more in width at the point where it engages the link of the trace chain to prevent friction and give strength.

To attach the device you remove the detachable fastening plate C' and engage the 55 hook F in the staple B and one of the links of the trace chain in the hook d.

When a trace strap is to be used instead of a trace chain a link or a few links of chain must intervene between the trace strap and 60 the hook d.

The invention is very simple and may be very quickly and easily attached to the hame staple or keeper, and the trace chain or strap.

Having thus described the invention, what 65 I claim, and desire to secure by Letters Patent, is—

The herein described hame clip or double hooked base consisting of a hook adapted to be connected to the trace, a hook connected 70 to the hame staple and a detachable fastening plate C for closing both hooks. The projection D on the clip or double hooked base passing through the slot E in the fastener and locked by the key G substantially as specified. 75

In testimony that I claim the foregoing as my own I have hereunto affixed my signature in the presence of two witnesses.

ALPINE B. ROSSON. [L. S.]
